Primary Examiner — Ian Simmons*Assistant Examiner* — Keith Frank(74) *Attorney, Agent, or Firm* — Cynthia Miller; Peter Giancana(57) **CLAIM**

The ornamental design for a fragrance bottle, as shown and described.

DESCRIPTION

FIG. 1 is a perspective view of my new design for a fragrance bottle;

FIG. 2 is a rear elevation view of the fragrance bottle, shown in FIG. 1;

FIG. 3 is a front elevation view of the fragrance bottle, shown in FIG. 1;

FIG. 4 is a left side elevation view of the fragrance bottle, shown in FIG. 1;

FIG. 5 is a right side elevation view of the fragrance bottle, shown in FIG. 1;

FIG. 6 is a top plan view of the fragrance bottle, shown in FIG. 1;

FIG. 7 is a bottom plan view of the fragrance bottle, shown in FIG. 1; and,

FIG. 8 is an exploded perspective view of the fragrance bottle, shown in FIG. 1.

The broken lines in the drawings showing the fragrance bottle illustrate the portions of the fragrance bottle that form no part of the claimed design.

1 Claim, 5 Drawing Sheets(56)
